UNITED STATES PATENT OFFICE.

CARL T. SCHUNK, OF LAKWOOD, OHIO, ASSIGNOR TO THE PEERLESS PAPER BOX MANUFACTURING COMPANY, OF CLEVELAND, OHIO, A CORPORATION OF OHIO.

METHOD OF FORMING DRY-BATTERY STRUCTURES.

Application filed January 14, 1928. Serial No. 246,898.

This invention relates to a method of making dry battery structures, such as the radio B-battery forming the subject matter of my co-pending application filed of even date 5 herewith, Serial No. 246,764.

The general object of the present invention is the provision of an improved method of making radio B-batteries of the character described, to the end that the parts thereof, 10 including the line attaching clips, may be easily, quickly and inexpensively assembled, and the completed batteries neat and attractive in appearance, efficient and not likely to get out of order in use.

15 Further objects of the invention are in part obvious and in part will appear more in detail hereinafter.

In the drawings, which illustrate the battery in its various stages of assembly, Fig. 1 is a plan view of the tray in which are arranged the series of battery cells; Fig. 2 is a similar view with the compartment forming partitions arranged in the tray; Fig. 3 is a view similar to Fig. 2 and showing the 20 cells arranged in said compartments; Fig. 4 is a front view of the supporting member for the line attaching clips; Fig. 5 is a similar view with the clips attached to said member; Fig. 6 is a view similar to Fig. 3 but showing the cells connected to each other and the line attaching clips, on their supporting member, connected to three of said cells; Figs. 7 and 8 are respectively a plan view and a side elevation of the tray arranged in suitable clamping means, with a sealing compound supplied to the tray; Fig. 9 is a view similar to Fig. 7 but with the clamping means removed and the tray supplied with a removable cover member; Fig. 30 10 is a perspective view of the tray enclosing casing, with the front end of said casing opened out; Fig. 11 is a perspective view of the rear end portion of said casing; Fig. 12 is a side elevation of the casing with the tray partially inserted thereinto; Fig. 13 is a similar view with the tray entirely within the casing and the front end of the casing in partially closed position; and Fig. 14 is a perspective view of the front end portion of 45 the completed battery structure.

The battery structure made by the method of the present application includes a tray in which are arranged a series of battery cells, said tray being of any suitable shape, such as rectangular, and of any suitable inex-

pensive material, such as light cardboard, preferably in a single sheet. Said tray comprises a bottom 1, end walls 2 and 3, and side walls 4 and 5, the latter wall being provided with an edge extension 6 for securing, such as by gluing, to the inner marginal surface of the end wall 2.

The top of the tray is therefore open to receive the partitions 9, which may be of any suitable inexpensive material, such as 65 cardboard, said partitions being arranged in intersecting relation so as to form a plurality of cell receiving compartments 10. In the present embodiment of the invention, a battery structure having a capacity of forty-five volts is to be made, so that nine intersecting partitions are provided to form compartments for thirty cells 11 of one and a half volts each. Said cells are of the usual form, having a cylindrical zinc casing 12 75 and a centrally disposed carbon rod 13, and are arranged in the compartments 10 in upright position, as clearly indicated in the drawings.

These radio B-batteries are provided with 80 three line attaching clips, each of which is connected to a battery cell. These clips may be of any suitable type, and in the present embodiment of the invention, Pfannstock clips are illustrated each of which is provided with a line attaching portion 15 and a rear end portion 16 for connection by soldering to a battery cell.

The clip indicated by the reference character 18 is for connection to a radio A-battery and is therefore soldered to the zinc casing of the first cell; the clip indicated by the reference character 19 is for connection to the plate member of a radio detector tube and is therefore soldered to the carbon rod of the fifteenth cell, thereby obtaining an output of twenty-two and one-half volts; and the clip indicated by the reference character 20 is for connection to either the plate member of a radio detector tube or the plate member of a radio amplifying tube and is therefore soldered to the carbon rod of the thirtieth cell, thereby obtaining an output of forty-five volts.

In order to hold said clips in proper 105 spaced relation for soldering to the first, fifteenth and thirtieth cells, a supporting member 22 is provided, which member is of substantially the same size as the tray side wall 4 against which it is secured. This 110

supporting member 22 may be of any suitable inexpensive material sufficiently rigid for the purpose, such as medium weight cardboard. Three transverse slots 24 are 5 provided in said supporting member near one of its longer edges to receive the rear or connecting end portions 16 of the clips, and similar slots correspondingly positioned are provided in the tray side wall 4.

10 In assembling the battery structure, the clips are first arranged in the slots of the supporting member 22 and the projecting rear end portions 16 of said clips are then pushed inwardly through the slots of the 15 tray side wall 4, which places said end portions in proper position for connection to their respective cells. The three clips are soldered to their cells and the series of cells are interconnected by wires 27, soldered 20 thereto, the carbon rod of each cell being connected to the zinc casing of an adjacent cell, as is usual.

After the cells have been interconnected by wires 27 and the clips connected to their 25 respective cells, as indicated in Fig. 6, the tray of cells is arranged in suitable clamping means 30 and a suitable sealing compound 31 is poured into the tray, more or less filling the spaces between partitions and cells 30 and covering the tops of the cells to a greater or less degree. A cover member 32, of any suitable material, such as corrugated cardboard, is then applied to the top of the tray, either while said tray is in the clamping 35 means 30 or after it has been removed therefrom, the upper surface of said cover member being preferably substantially flush with the top of the tray.

The tray of battery cells thus formed is 40 enclosed within a casing of any suitable inexpensive material, such as light cardboard, preferably in a single sheet and provided with the necessary fold lines to enable the casing to be readily formed. Said casing 45 includes a top portion 35, a bottom portion 36 and two side portions 37 and 38, the latter portion being provided with an edge extension 39 for connection, by gluing or the like, to the inner surface of the adjacent margin 50 of the top portion 35. The casing side portions are each provided at their rear ends with an extension 40 and the casing top and bottom portions are each provided at their 55 rear ends with an extension 41. These four extensions form the rear end wall of the casing and by gluing or otherwise suitably connecting the extensions 40 and 41 to each other, the rear end of the casing is permanently closed. The extensions 40 are 60 preferably arranged inside of extensions 41, which are preferably of such size as together almost completely close the rear end of the casing.

The casing bottom portion 36 is provided 65 at its front end with a rather large extension which includes a portion 43 forming the

front end wall of the casing. Said portion 43 is provided at each of its two sides with a sealing flap 44 and at its front free end with a sealing flap 45. These three flaps are adapted to be inserted within the casing and 70 glued or otherwise suitably secured to the inner surface of the side and top portions of the casing as indicated in dotted lines, Fig. 14. Preferably, and as shown, the edge extension 39 has its front end portion cut 75 away, as at 46, so that it will not interfere with the insertion into the casing of the sealing flap 45.

The front wall 43 of the casing is provided 80 with three openings 48 so positioned or spaced that when the front end of the casing is closed, as in Fig. 14, the line attaching portions 15 of the three clips 18, 19 and 20 will project out through said openings and therefore be readily accessible for attachment of the lines or wires 49.

The several steps of the present method are therefore as follows:

The arrangement of the partitions 9 in the tray; the placing of a battery in each 90 compartment formed by said partitions; the mounting of the line attaching clips under their supporting member; the assembly of said supporting member, through the medium of said clips, with the side wall 4 of 95 the tray; the interconnecting by soldering of the cells and the connection of said clip by soldering to three cells; the application of clamping means to the tray; the supply 100 of the sealing compound; the application of the removable cover member; the removing of said clamping means (this step may precede the application of the cover member); the insertion of the tray within the enclosing casing; and the closing and sealing 105 of the front end of the casing, leaving the attaching portions of the clips exposed for attachment of the wires 49.

What I claim is:

1. The method of making dry battery 110 structures, consisting in arranging a plurality of cells in a container, mounting a plurality of line attaching clips upon a supporting member, and interconnecting said cells by wires soldered thereto and soldering said clips while upon said member to certain of said cells, thereby permanently assembling said supporting member with said clips.

2. The method of making dry battery 115 structures, consisting in arranging a plurality of cells in a container having one of its walls provided with a plurality of apertures, mounting a plurality of line attaching clips upon a supporting member with portions of said clips projecting from said member, inserting said projecting portions through the apertures in said casing wall, and soldering 120 said clip portions to certain of said cells.

3. The method of making dry battery 125 structures, consisting in arranging a plural-

ity of battery cells in a container having one of its walls provided with a plurality of apertures, inserting the connecting end portions of a plurality of line attaching clips 5 through a plurality of openings in a supporting member for said clips, with said clip connecting portions projecting from said member, inserting said projecting clip portions through the apertures of said casing 10 wall, and soldering said inserted clip portions to certain of said battery cells.

4. The method of making dry battery structures, consisting in arranging a plurality of battery cells in an open top tray having one of its side walls provided with a plurality of apertures, inserting the connecting end portions of a plurality of line attaching clips through a plurality of openings in a supporting member for said clips, 15 with said clip connecting portions projecting from said member, inserting said projecting clip portions through the apertures of said tray wall, soldering said inserted clip portions to certain of said battery cells, 20 and providing said tray with a cover member.

5. The method of making dry battery structures, consisting in arranging a plurality of intersecting partitions in a container so as to provide a series of compartments in said container, arranging a battery cell in each of said compartments, said container having one of its walls provided with a plurality of apertures, inserting the connecting portions of a plurality of line attaching clips through openings in a supporting member for said clips, with said clip connecting portions projecting from said member, inserting said projecting clip portions 30 through the apertures of said container wall, and soldering said inserted clip portions to certain of said cells, which secures said supporting member in assembled relation with said clips.

45 6. The method of making dry battery structures, consisting in arranging a plurality of battery cells in a container having one of its walls provided with a plurality of apertures, inserting the connecting portions of a plurality of line attaching clips through openings in a supporting member for said clips with said clip connecting portions projecting from said member, inserting said projecting clip portions through the apertures of said container wall, soldering said inserted clip portions to certain of said battery cells, which secures said supporting member in assembled relation with said clips, interconnecting said cells by wires 50 soldered thereto, and pouring a sealing compound into said container, so as to more or less fill the spaces between cells and cover said cells to a greater or less degree.

7. The method of making dry battery structures, consisting in arranging a plural-

ity of battery cells in an open top container having one of its side walls provided with a plurality of apertures, inserting the connecting portions of a plurality of line attaching clips through openings in a supporting member for said clips, with said clip connecting portions projecting from said member, inserting said projecting clip portions through the apertures of said container wall, soldering said inserted clip portions to certain of 70 said battery cells, which secures said supporting member in assembled relation with said clips, interconnecting said cells by wires soldered thereto, pouring a sealing compound into said container, so as to more or 75 less fill the spaces between cells and cover said cells to a greater or less degree, and applying a cover member to said container.

8. The method of making dry battery structures, consisting in arranging a plurality of battery cells in a container having one of its walls provided with a plurality of apertures, inserting the connecting portions of a plurality of line attaching clips through openings in a supporting member 85 for said clips, with said clip connecting portions projecting from said member, inserting said projecting clip portions through the apertures of said container wall, soldering said inserted clip portions to certain of said 90 battery cells, which secures said supporting member in assembled relation with said clips, interconnecting said cells by wires soldered thereto, and placing the aforementioned parts in an enclosing casing. 100

9. The method of making dry battery structures, consisting in arranging a plurality of battery cells in a container having one of its walls provided with a plurality of apertures, inserting the connecting portions of a plurality of line attaching clips through openings in a supporting member for said clips, with said clip connecting portions projecting from said member, inserting said projecting clip portions through the apertures of said container wall, soldering said inserted clip portions to certain of said 105 battery cells, which secures said supporting member in assembled relation with said clips, interconnecting said cells by wires soldered thereto, and placing the aforementioned parts in an enclosing casing provided with a plurality of openings in one of its walls to permit portions of said clip to project therethrough. 110

10. The method of making dry battery structures, consisting in arranging a plurality of battery cells in a container having one of its walls provided with a plurality of apertures, inserting the connecting portions of a plurality of line attaching clips through openings in a supporting member for said clips, with said clip connecting portions projecting from said member, inserting said projecting clip portions through the 115 120 125

- apertures of said container wall, soldering said inserted clip portions to certain of said battery cells, which secures said supporting member in assembled relation with said 5 clips, interconnecting said cells by wires soldered thereto, and inserting the aforementioned parts in an enclosing casing having all but one of its walls permanently closed, said one wall being openable to permit the 10 insertion of said parts and being provided with openings to permit portions of said clips to project therethrough.
11. The method of making dry battery structures, consisting in arranging a plurality 15 of battery cells in an open top container having one of its side walls provided with a plurality of apertures, inserting the connecting portions of a plurality of line at-
- taching clips through openings in a supporting member for said clips, with said clip 20 connecting portions projecting from said member, inserting said projecting clip portions through the apertures of said container wall, soldering said inserted clip portions to certain of said battery cells, which 25 secures said supporting member in assembled relation with said clips, interconnecting said cells by wires soldered thereto, applying confining means to said container, and pouring a sealing compound into said 30 container so as to more or less fill the spaces between cells and cover said cells to a greater or less degree.

In testimony whereof I hereby affix my signature.
